UNITED STATES PATENT OFFICE.

JOSEPH BARKER, OF CARSON CITY, NEVADA.

LUMBER-TRUCK.

SPECIFICATION forming part of Letters Patent No. 740,613, dated October 6, 1903.

Application filed December 11, 1902. Serial No. 134,821. (No model.)

To all whom it may concern:

Be it known that I, JOSEPH BARKER, a citizen of the United States, residing at Carson City, in the county of Ormsby and State of Nevada, have invented a new and useful 5 Lumber-Truck, of which the following is a specification.

My invention relates to mechanism for conveying lumber to and fro between a lumber pile and car for loading or unloading the latter; and it has for its objects to produce a portable mechanism of this character which will be simple in construction and operation and which may be readily transferred from 15 point to point as circumstances may require, the mechanism as a whole embracing an improved car for conveying the lumber and an improved track therefor of such construction that while being strong and durable it will 20 be of sufficient lightness to insure its ready removal from place to place.

To these ends the invention comprises in a lumber-truck the combination, with a plurality of axles, of a horizontal brace-rod connecting the same and a roller mounted on said brace-rod.

The invention further comprises the details of construction and combination of parts more fully hereinafter described.

30 In the accompanying drawings, Figure 1 is a side sectional elevation of my improved mechanism. Fig. 2 is a sectional end elevation of the same. Fig. 3 is a perspective view of the pivotal connection for the rail-sections. Fig. 4 is a diagrammatic view illustrating the 35 device in operation.

Referring to the drawings, 1 indicates my improved truck, comprising axles 2 2, having their ends bent downward and outward, forming 40 spindles on which the supporting-wheels 3 are mounted. This manner of bending the axle produces arches 4 for the purpose hereinafter explained. 5 is a connecting-rod having reduced ends 6, which are mounted in 45 bearings 7, formed at the center of the arched axles and receiving suitable nuts for securing the parts together. It is to be noted that the reduced ends 6, which receive the nuts, are shouldered, as at 8, to prevent the nuts, 50 binding against the axle. Mounted upon the rod 5 are a series of short rollers 9. These rollers are each preferably constructed of a

suitable length of metal tubing having blocks 10 inserted and suitably secured in its ends, the blocks being provided with a central hole 5 by means of which they are journaled on the rod 5. While I have illustrated a plurality of these rollers 9 as being mounted on the rod, it is to be understood that they may be substituted by a single roller, if so desired. 60

While the above-described truck is susceptible of being employed in connection with any suitable track, I prefer to use the one herein shown. This track comprises a plurality of rail-sections 11, of suitable lengths, 65 arranged end to end and having their meeting ends pivoted. These sections may be pivoted in any suitable manner; but I prefer to form on the end of one section a round lug or pivotal axis 12, adapted to be seated 70 within a socket 13, formed on the meeting end of the next section. I also bevel the vertical ends of the sections downward and away from the pivotal point, as at 14, thus permitting one section to be moved vertically 75 up or downward with relation to the other. I provide chairs formed for supporting the rails 11 by bending the lower end of a steel plate 15 outward to form a horizontal lateral flange 16, which lies beneath the rail. The 80 plate 15 extends vertically upward along the side of the rail at a point near its top and is then bent inward and upward, as shown.

17 indicates brace- rods having vertical downwardly-extending ends 18, which lie 85 against the inner vertical faces of the plate 15. These braces extend obliquely upward to a point near the top of the plate 15, where they are provided with ears through which are passed rivets to secure them and the plate 90 15 together.

19 indicates bolts or rivets by which the rails, plates, and braces are securely connected together at the point where the rail-sections are pivoted together. The ends of the plates 95 15 are beveled, as at 20, vertically upward and outward away from the pivotal point. I also reduce the height of the plates 15 at the pivotal point, as shown in Fig. 2, for the purpose 100 to be presently explained.

When my improved car is mounted for travel upon the tracks 11, the arched axles will, as shown in Fig. 2, override the tops of the plates 15, and the plates being reduced in

height at the pivotal point prevent the axles coming in contact with the tops of the plates when one rail-section is turned downward with relation to the other.

- 5 In operation the rail-sections, which may be disengaged for transportation, are laid in two lines, as illustrated in Fig. 4, from the lumber-pile to the point to which the lumber is to be conveyed, and a truck is placed upon 10 each of these lines, the lumber to be moved being loaded upon the two trucks with its ends resting upon the rollers 9, carried by the respective trucks, and the trucks are moved forward by hand. When the point at which 15 the lumber is to be unloaded is reached, the rollers permit the lumber being shoved freely from the trucks, the lumber, of course, moving across the rollers transversely of the trucks, thus preventing any cramping or binding 20 of the parts. From this it will be seen that if the lumber is to be loaded onto a car or a dray the trucks may be brought to a suitable position at the end thereof and the lumber shoved freely from the same into the 25 car or dray.
- It will be seen that by the above construction I produce a very light and simple sectional track which may be readily disengaged for transportation and a truck which is 30 admirably adapted for use in connection with this track, and it is to be understood that I

do not limit myself to the details of construction herein shown and described, as various changes may be made therein without departing from the spirit or scope of my invention. 35

Having thus fully described my invention, what I claim as new, and desire to secure by Letters Patent, is—

1. In a lumber-truck, the combination with a plurality of axles, of a horizontal brace-rod connecting the same, and a roller mounted on the brace-rod. 40
2. In a lumber-truck, the combination with a plurality of axles, of a central horizontal rod connecting the same and a plurality of 45 rollers mounted end to end upon said rod.
3. In a lumber-truck, the combination with a plurality of arched axles, of a horizontal brace-rod connecting the same, and a roller mounted on the brace-rod. 50
4. In a lumber-truck, the combination with a plurality of arched axles, of bearings carried thereby, a horizontal brace-rod mounted in said bearings, and a roller mounted on the brace-rod.

In testimony that I claim the foregoing as my own I have hereto affixed my signature in the presence of two witnesses.

JOSEPH BARKER.
